Primary Examiner — Susan Bennett Hattan*Assistant Examiner* — Omeed Agilee(74) *Attorney, Agent, or Firm* — Goodwin Procter LLP(57) **CLAIM**

The ornamental design for a vial adapter, as shown and described.

DESCRIPTION

FIG. 1 is a front perspective view of a vial adapter;
FIG. 2 is a front view of the vial adapter;
FIG. 3 is a rear view of the vial adapter;
FIG. 4 is a right side view of the vial adapter;
FIG. 5 is a left side view of the vial adapter;
FIG. 6 is a top view of the vial adapter;
FIG. 7 is a bottom view of the vial adapter; and,
FIG. 8 is a rear perspective view of the vial adapter.
The evenly spaced broken lines shown in the drawings
depict portions of the vial adapter that form no part of the
claimed design.
